HAT HOLDER

Charles W. Twite, New York, N. Y.

Application September 9, 1935, Serial No. 39,815

2 Claims. (Cl. 24—255)

This invention relates to hat clamps or hangers and more particularly to individual hat clamps for attachment to the back of seats or other suitable supporting structures.

5 The object of this invention is to provide a device of this character that is both simple in construction and efficient in use which may readily be attached to the back of any chair, pew or theatre seat for clamping a hat thereto and when 10 not in use may be placed in the pocket of the owner.

Another object of the invention relates to the provision of an auxiliary clamping means that is secured to the hat clamp proper which is adapted 15 to be used for supporting an additional hat such as for example, a lady's hat.

Further objects of this invention are to provide a hanger of the above mentioned character, which consists of but comparatively few parts, 20 that is economical in manufacture, may be retailed at low cost and positive and efficient in operation, practical, reliable, and otherwise well adapted for the purpose for which it is designed.

In the accompanying drawing:—

25 Figure 1 is an enlarged side elevational view of the hanger constructed in accordance with this invention and showing the application of the same for supporting a hat from the upper edge of a chair back or pew.

30 Figure 2 is a front elevational view of the hanger.

Figure 3 is a detail sectional view taken on line 3—3, Figure 2.

Figure 4 is a side view showing a hat clamped 35 to the back of a chair, pew or theatre seat.

Figure 5 is a side elevational view of an auxiliary clamping device attached to the hanger proper.

Referring again to the drawing, the hanger 10 40 is preferably made of flat thin spring stock finished in any suitable manner and as shown in Figure 1 comprises a straight front portion 11, a rounded bight portion 12 and a curved clamp portion 13 that is convexly curved towards the 45 straight portion 11 and extends a substantial distance beyond the same.

Adjacent the lower end 14 of the hanger 10 is provided a friction clamp 15 that is preferably made of rubber in the form of a button. The 50 rubber button 15 is rigidly secured to the inner face 16 of the hanger 10 by means of a rivet or screw 17.

In use, the hanger 10 is slipped over the upper edge 20 of a chair back, pew or other supporting 55 structure. In Figures 1 and 4, the hanger 10 is

shown mounted on the upper edge of the back 21 of a church pew 22, the brim 23 of the hat 24 being clamped between the back 21 and the rubber button 15 as clearly shown. It is to be understood that the relationship of the straight 5 portion 11 to the curved portion 13 of the hanger 10 should be such, that when the hanger 10 is slipped over the back 21, the curved portion 13 of the hanger will become tensioned so as to produce a clamping pressure on the hat brim 23 10 sufficient to hold the same clamped against the back 21. The rubber button 15 presenting a friction gripping surface will act to additionally prevent the hat from slipping out of its clamped engagement, in the manner readily apparent. 15

In the modification shown in Figure 5, the lower end 14 of the hanger 10 has movably attached thereto one end of a chain 25 the other end thereof carrying a resilient clamp 26 which is adapted for attachment to a lady's hat (not 20 shown) to hold the same simultaneously with the holding of a man's hat by the hanger 10 proper. The clamp 26 is preferably made of flat spring stock with the prongs 27 normally in resilient engagement with each other. It is to be 25 understood that the form of clamp 26 may be replaced by any suitable type of clamping means that will serve to hold a lady's hat. Also the clamp 26 may be attached to the hanger 10 by any form of flexible or rigid means. 30

The novel features and the operation of this device will be apparent from the foregoing description. While the device has been shown and the structure described in detail, it is obvious that this is not to be considered limited to the 35 exact form disclosed and that changes may be made therein within the scope of what is claimed, without departing from the spirit of the invention.

Having thus set forth and disclosed the nature 40 of this invention, what is claimed is:

1. A hanger for hats adapted to be hooked over a supporting member comprising a spring member formed of flat thin spring stock provided 45 with spaced arms joined by a curved bight portion, one of said arms being straight and the other of said arms being of a greater length and convexly curved towards said straight arm, and a rubber button rigidly secured to said curved arm adjacent the free end thereof and arranged 50 in opposed relation to said straight arm.

2. The hanger as specified in claim 1, including an auxiliary hat clamping means flexibly attached to one of the arms of said hanger. 55

CHARLES W. TWITE.
